UNITED STATES PATENT OFFICE

106,443

DESIGN FOR A DISH OR SIMILAR ARTICLE

Adolph Jungwirth, Prague, Czechoslovakia

Application July 15, 1937, Serial No. 70,461

Term of patent 3½ years

To all whom it may concern:

Be it known that I, Adolph Jungwirth, a citizen of Czechoslovakia and a resident of Prague, Czechoslovakia, have invented a new, original, and ornamental design for a Dish or Similar Article, of which the following is a specification, reference being had to the accompanying drawing forming part thereof.

Fig. 1 shows a plan view of a dish or similar article showing my new design; and

Fig. 2 shows a front elevational view of the same.

The dominant feature of the design resides in the handles of the dish and of the handle of the cover.

I claim:

The ornamental design for a dish or similar article, substantially as shown and described.

ADOLPH JUNGWIRTH,
